REFRIGERATOR

Filed Aug. 12, 1926

Inventor

GEORGE W. MASON

By

Henry Barnes

Attorney

UNITED STATES PATENT OFFICE

GEORGE W. MASON, OF DETROIT, MICHIGAN, ASSIGNOR TO COPELAND PRODUCTS, INC.,
OF DETROIT, MICHIGAN, A CORPORATION OF MICHIGAN

REFRIGERATOR

Application filed August 12, 1926. Serial No. 128,734.

The primary object of my invention is to provide within a mechanically operated refrigerator, means for forming a supply of ice during the period of operation of the refrigerating machine which will serve to cool the food storage compartment of the refrigerator during the periods when the refrigerating machine is not in operation.

Another object of my invention is to provide a secondary means of cooling a mechanically operated refrigerator which will permit long periods of inactivity of the refrigerating machine.

A further object of my invention is to provide a means within a mechanically operated refrigerator for making an extra supply of ice when the usual ice trays used for that purpose are not of sufficient capacity for the occasion.

With these and other objects in view, my invention consists in the arrangement, combination and construction of the various parts of my improved device, as described in the specification, claimed in my claims and shown in the accompanying drawing, in which:

The single figure is a front elevation of a refrigerator with certain parts broken away showing an embodiment of my invention therein.

I have shown a conventional type refrigerator 1 having the motor, compressor and condenser of the refrigerating apparatus (not shown) positioned within the upper portion 35 2 of the cabinet 1. The expansion chamber or freezer 3 of the refrigerating apparatus is positioned in the upper portion of the food storage compartment 4 of the cabinet 1, and is connected with the compressor and condenser (not shown) in the upper portion 2. Ice trays 8 are removably positioned within the expansion chamber 3.

Beneath the expansion chamber 3 is positioned a drip pan 5 with its upturned edges 6 secured to the sides of the compartment 4. Inserted through the bottom of drip pan 5 and extending downward through the bottom of the cabinet 1 is a drain pipe 7. The upper end of the drain pipe 7 is extended 50 above the bottom of drip pan 5 a sufficient

distance to permit a desirable amount of water to accumulate and remain at all times in the drip pan 5. The water so accumulating in drip pan 5 is formed by the melting, during the inoperative periods of the refrigerating apparatus, of the frost which accumulates upon the expansion chamber during the operating periods.

A constant level of water will be maintained in the drip pan 5 by the drain pipe 7 which will drain away the excess water when the level reaches its extended open end in the drip pan.

A second drip pan 9 for receiving any water that may be formed by the melting of frost which may accumulate on the outside of drip pan 5, is positioned beneath drip pan 5 with its upturned edges 10 secured to the sides of compartment 4. The drain pipe 7 also extends through the bottom of drip pan 9 and has an opening 11 therein through which any water received by the drip pan 9 will drain away.

In operation, the refrigerating apparatus will, during the freezing period cause the water in the drip pan 5 to freeze solid and thus provide a supply of ice which will serve to cool the food storage compartment 4 when the refrigerating machine is not running, and which will also permit longer periods of inactivity for the machine.

The drip pan may also be used to make extra quantities of ice where a greater quantity than can be made in the usual ice trays 8, is desired.

It will be obvious that various changes may be made in the arrangement, combination and construction of the various parts of my improved device without departing from the spirit of my invention, and it is my intention to cover by my claims such changes as may be reasonably included within the scope thereof.

What I claim is:

1. In a refrigerating cabinet, an expansion element, a container below said element adapted to receive drippings from said element, a second container below the first mentioned container adapted to receive drippings therefrom, and means for limiting the

level of said drippings in the first mentioned container to a point between the top and bottom thereof and for draining the second mentioned container.

5. 2. In a refrigerator cabinet, an expansion element, a freezing container positioned below and adjacent said element whereby to receive drippings therefrom, a second container below the first mentioned container
10 adapted to receive drippings from said first mentioned container, and a drain tube projecting upwardly through both of said containers, said tube terminating between the top and bottom of said first mentioned container, and an opening in said tube within
15 said second container substantially in the plane of the bottom thereof.

GEORGE W. MASON.
